(57) **CLAIM**

The ornamental design for a gripping handle end, as shown and described.

DESCRIPTION

FIG. 1 is a perspective view of a gripping handle end of the invention; and

FIG. 2 is a perspective view thereof showing a use environment;

FIG. 3 is a side view thereof with all sides being identical;

FIG. 4 is a plan view thereof; and

FIG. 5 is a bottom view thereof.

The broken lines illustrate environmental elements of a gripping handle end which forms no part of the claimed design.
